UNITED STATES PATENT OFFICE.

JOSEPH T. LINDSEY, OF LEOMINSTER, MASSACHUSETTS.

SANDING-MACHINE.

1,246,958.

Specification of Letters Patent. Patented Nov. 20, 1917.

Application filed August 17, 1916. Serial No. 115,524.

To all whom it may concern:

Be it known that I, JOSEPH T. LINDSEY, a citizen of the United States, residing at Leominster, in the county of Worcester and 5 Commonwealth of Massachusetts, have invented a new and useful Improvement in Sanding-Machines, of which the following, together with the accompanying drawings, is a specification.

- 10 The object of my present improvement is to provide a sanding machine for the purpose of rounding the corners of woodwork and producing a uniform curvature in place of a rectangular corner.
- 15 I am aware that sanding machines have been devised for the purpose of abrading and polishing circular articles. The purpose of my present invention, however, is to render an angular surface curved with 20 a uniform curvature extending equally upon opposite sides of the angle treated. I accomplish this result by the construction and arrangement of parts as hereinafter described, the novel features being pointed 25 out in the appended claims.

Referring to the accompanying drawings,

Figure 1 is a plan view of my improved sanding machine.

- 30 Fig. 2 is a side elevation, shown in section, on the plane of the broken line 3—3, Fig. 1, and

Fig. 3 is a side elevation of the stand for supporting the pulleys for supporting the 35 sanding belts in proper position to contact with the work, and illustrating the adjusting mechanism by which said pulleys are raised or lowered.

- Similar reference characters refer to 40 similar parts in the different figures.

The framework of my machine comprises posts 1, 1 at the corners of the framework, cross girths 2 near the bottom of the frame, upon which is supported a shaft 3 provided 45 with tight and loose pulleys 4 and 5 and a drum 6, by which motion is imparted to the sanding belts 7, 8 and 9. The sanding belts 7, 8 and 9 are supported near the top of the machine by pulleys 10, 11 and 12, supported in yokes 13, 14 and 15, said yokes being capable of sliding in ways formed in a casting 16 mounted upon a girth 17 forming a portion of the framework.

- The yoke 14 is adjusted in a vertical 50 plane by means of a screw 18, and the yokes 13 and 15 are adjusted by screws 19 and 20

in ways which converge toward the top of the machine. The sanding belts 7, 8 and 9 are tightened by means of tightening pulleys 21, 22 and 23 carried on the ends of 60 levers 24, 25 and 26, said levers being arranged at one end of the framework of the machine and being drawn upward to press the tightening pulleys against the belts by springs 27 and eyebolts 28.

65 Mounted upon the top of the framework is a supporting trough for the work to be sanded consisting, in the present instance, of the sides 29 and 30, placed at an angle of forty-five degrees to each other, and forming 70 a right angled bed 32 on which the work is supported, bearing against the opposite sides of the trough, as represented in Fig. 2, in which the piece of work to be sanded is represented at 31. At the bottom of the 75 trough is an opening 33 extending over the pulleys 10, 11 and 12, of sufficient width to allow the sanding belts to be brought in contact with the corner of the work.

In the operation of the machine the piece 80 of work to be treated is moved longitudinally through the trough 32, with one of its corners fitting the right angled corner of the trough, as represented in Fig. 2. The outer corner of the trough 32 is cut away, as 85 shown in Fig. 2, to provide for the vertical adjustment of the pulleys 10, 11 and 12, which are so adjusted as to remove the requisite amount of stock to produce a rounded corner. The yokes carrying the outer pulleys 10 and 12 are adjustable in ways placed 90 at the proper angle to coöperate with the central pulley 11 to produce a corner of the desired curvature. While the abrasion of the stock is in a line transverse to the corner, 95 the required amount to be removed by each of the sanding belts is so slight that, by the proper adjustment of the pulleys 10, 11 and 12, the contacting surfaces of each of the three sanding belts 7, 8 and 9 will produce 100 a corner of the desired curvature. When the desired rounding of the corner has been secured by the adjustment of the pulleys 10, 11 and 12, the abrasion of the stock will be uniform throughout the entire 105 length of the corner as the work is moved longitudinally in the trough 32.

The rounding of right angled corners is very desirable in work to be used in many classes of finished furniture, such, for example, as piano cases where several coats of varnish are applied and successively rubbed,

When the corners of woodwork are rounded by moving an abrasive substance, such as sand paper, lengthwise the corner, the amount of stock removed is liable to vary, 5 not only between different pieces but also between different parts of the same piece. My method of rounding the corners avoids this irregularity by moving the belts transversely of the movement of the piece of 10 work, and also by supporting the abrasive belt during its contact with the work upon the periphery of an unyielding roll.

I claim,

1. In a machine of the class described, a 15 framework, a drum journaled therein, a multiplicity of abrading belts carried by said drum, a pulley for each of said belts, and a trough for supporting the work with a corner of the work exposed to the action 20 of said belts.

2. In a machine of the class described, an angular trough for supporting the work, a multiplicity of abrading belts, said trough having an opening through which a corner 25 of the work is exposed to said belts, and idler pulleys for holding said belts in contact with the work.

3. In a machine of the class described, an angular trough for supporting the work, a 30 multiplicity of abrading belts, said trough having an opening through which a corner of the work is exposed to said belts, idler pulleys for supporting said belts in contact with the work, means for adjusting said 35 idler pulleys relatively to the work, and means for driving said belts.

4. In a machine of the class described, an angular trough for supporting the work with one of its corners exposed, a multiplicity

40 of abrading belts, means for driving said belts transversely to the work, idler pulleys for holding said belts in contact with the work, and means for the independent adjustment of each of said idler pulleys toward or away from the work. 45

5. In a machine of the class described, a multiplicity of abrading belts, a trough for supporting the work with one of its corners exposed to said belts, a pulley for each of 50 said belts, whereby the belt is held in contact with the work as it passes around the pulley, and means for adjusting said pulleys relatively to the work.

6. In a machine of the class described, an angular trough for supporting the work 55 and having an opening at its apex through which a corner of the work is exposed, three abrading belts, pulleys for carrying each of said belts, with the axis of one pulley in alinement with the apex of said trough and 60 with the axes of the remaining pulleys on opposite sides of said central pulley, and means for independent adjustment of each of said pulleys relatively to said trough.

7. In a machine of the class described, a 65 series of abrading belts, an angular trough for supporting the work in position to present a corner to the action of said belts, means for moving the belts transversely to the work, a series of pulleys for supporting 70 the belts while in contact with the work, and means for holding said pulleys in staggered relation to each other.

JOSEPH T. LINDSEY.
